UNITED STATES PATENT OFFICE.

CHARLES GARRABRANT, OF BROOKLYN, NEW YORK.

RADIO SWITCH.

Application filed December 21, 1925. Serial No. 76,808.

This invention relates to new and useful improvements in radio apparatuses, and particularly to switches therefor.

One object of the invention is to provide a device of this character which automatically controls the radio set, so that said set may be operated at any time desired, without manipulation.

Another object is to provide a device of this character wherein the set will be started at a particular hour of the day or night, in accordance with the operation of a timepiece.

Another object is to provide a means which permits the operation of the set after having been automatically actuated, whereby to provide for manipulation of the dials, to bring in other stations, and to prevent the timepiece from again opening the circuit.

Other objects and advantages will be apparent from the following description when taken in connection with the accompanying drawings.

In the drawings:

Figure 1 is a top plan view of the unit containing the automatic switch.

Figure 2 is a vertical transverse sectional view on the line 2—2 of Figure 1, showing the switch in rear elevation.

Figure 3 is a side elevation of the clock controlled mechanism and switch, and including, in diagram, the wiring to the set.

Figure 4 is a detail perspective view of the rotary portion of the switch.

Figure 5 is an elevation of the winding and setting controls of the clock.

Referring particularly to the accompanying drawings, there is shown a unit which includes the loud speaker 10, the clock 11, the plug jacks 12 and 13, and the controlling switch, represented as a whole by the numeral 14.

A radio receiving set, of which a tube socket 15, battery terminal 16, and the plug jack 17, are shown, is adapted to be located at any suitable point with respect to the above-mentioned unit. Plugs 18 and 19, at opposite ends of the conductor cord 20, are adapted to be inserted in the jacks 12 and 17, respectively, of the unit and set. The jack

17 has one terminal connected to the positive binding post of the socket 15, as shown at 22, while the other terminal is connected to the negative B battery post of the terminal 16.

The winding arbor 24, of the alarm mech-

anism of the clock 11, is extended through the rear wall of the unit, and is provided with a fingerpiece 23, while the minute hand arbor 25, the winding arbor 26, of the clock, and the alarm setting arbor 27, are also extended through the rear wall of the unit, in position to be manipulated to permit winding and setting of the clock and the alarm mechanism thereof. The arbor 24 is disposed through a vertical insulated post 28, and mounted on this post, above and below the arbor, are the contact members 29 and 30, said contact members being connected, respectively, to the terminals of the jack 12. Secured to the arbor 24, in transversely extending relation thereto, is a bar 31, and secured at one end to one end of the bar is a leaf spring 32. Mounted above, or on the clock, is a horizontal pivotal lever 33, one end of which is turned downwardly, at 34, in position to engage the free end of the leaf spring 32, to flex the latter away from the contact 29, the other end of the lever being disposed in position for ready manipulation.

The above mechanism is especially adapted for use in automatically turning on a radio receiving set at a particular time, when a concert, or other message is being broadcast from a station. The owner of the set turns the dials for the particular station, winds the clock, and sets the alarm mechanism to operate at the time at which the station is to broadcast. When the clock reaches the hour of broadcasting, the alarm arbor 24 will be released so that said arbor will rotate and cause the free end of the bar 31 to engage with the contact 30, and the free end of the leaf spring 32 to engage with the contact 29. It will be noted that the parts are so arranged and constructed that when the bar 31 engages the contact 30 the other end of the bar will be held in spaced relation to the contact 29 by means of the leaf spring, thus providing a yielding contact. Upon operation of the lever 33 the free end of the spring may be flexed out of contact with the contact member 29, thus opening the circuit, to cut out the radio set.

What is claimed is:

1. A switch including stationary contacts, a rotatable contact member adapted to engage one end with one of the stationary contacts, a flexible member on the rotatable member for engagement with the other sta-

tionary contact, and means for disengaging the flexible member from said contact.

2. A switch including stationary contacts, a rotatable contact one end of which is adapted to engage with one of the stationary contacts, a flexible member secured to the rotatable contact and arranged to engage its free end with the other stationary contact simultaneously with the engagement of the 10 other end of the rotatable contact with the first-named stationary contact, and means for moving the flexible member out of engage-

ment with the stationary contact without movement of the rotatable contact.

3. An electric switch including a rotatable 15 shaft, stationary contacts disposed on opposite sides of the shaft, means on the shaft for simultaneous engagement with the contacts upon rotation of the shaft in one direction, and means for disengaging one end 20 of the said shaft means without disengagement of the other end thereof.

In testimony whereof, I affix my signature.
CHARLES GARRABRANT.
